UNITED STATES PATENT OFFICE.

LOUIS W. ALBIZU, OF PONCE, PORTO RICO.

EXERCISING APPARATUS.

Application filed July 15, 1921. Serial No. 434,974.

To all whom it may concern:

Be it known that I, LOUIS W. ALBIZU, a citizen of the United States, and a resident of Ponce, Porto Rico, have invented a new and Improved Exercising Apparatus, of which the following is a full, clear, and exact description.

This invention relates to exercising devices and particularly to a weight or dumbbell and has for an object to provide a construction which may be used in the usual manner of dumb-bells and at the same time used in other forms of exercise.

Another object in view is to provide a weighted member readily grasped by the hand which presents anti-friction members to the floor or other surface against which it may be placed when exercising.

In the accompanying drawing—
Figure 1 is a side elevation of an embodiment of the invention with certain parts shown in section, said section being taken on line 1—1 of Figure 2.

Figure 2 is a sectional view through Figure 1 on line 2—2.

Referring to the accompanying drawing by numerals, 1 indicates a handle which is provided with a grip 2, enlarged ends 3 and 4, said ends having abutments or shoulders 5 and 6 and stub shafts 8 and 9 on which the end members or weights 10 and 11 are rotatably mounted. It is, of course, understood that the handle 1 and end members 10 and 11 may be made from wood, metal or any desired material and may be made of any desired weight. The end members 10 and 11 are substantially in the form of discs and are each provided with an annular groove 12 for receiving a rubber tire 13 whereby the device may be placed on the floor, wall or other surface and rolled along as part of an exercise.

It is also evident that the device could be used as an ordinary dumb-bell. A shaft or bolt 14 extends entirely through the handle 1 including the shafts 8 and 9, said bolt having a head at one end and a nut 15 at the opposite end clamping the washer 16 in

place. Preferably, the shafts 8 and 9 extend beyond the end weights 10 and 11 so that the nut 15 may be clamped firmly in place and yet allow ample play for the end members so they will freely rotate. Each of the end members is provided with a cap 17 hollowed out to accommodate the head and nut respectively of the bolt. Suitable securing screws 18 connect the caps with the respective end members 10 and 11.

It will be noted that the grip 2 is rounded to properly fit the hand and the enlargements 3 and 4 are also rounded while the facing surfaces of members 10 and 11 are chamfered or inclined.

What I claim is:

1. An exercising device comprising a handle, formed with a gripping portion, a pair of enlargements and a pair of stub shafts, said gripping portion, enlargement and shafts being integral, a rotatable disk acting as a weight mounted on each of said stub shafts, and means for holding the disks on the stub shafts without interfering with their rotation.

2. An exercising device comprising a handle provided with a grip and extensions on each end of the grip, a disc-shaped weight rotatably mounted on each of said extensions, each of said disc-shaped members having a rubber tire on the periphery, and means for locking the disc-shaped members on said extensions while permitting a free rotation thereof.

3. An exercising device of the character described comprising a handle formed with a grip, a pair of enlargements at each end of the grip and a projection extending from each of said enlargements, a rotatable weight mounted on each of said enlargements, a bolt extending through said handle and overlapping at each end the extensions for holding the rotatable weights in position on the projections, and a covering cap secured to each of the rotatable members covering the ends of said bolt.

LOUIS W. ALBIZU.
